(57) **CLAIM**

The ornamental design for a dispensing bottle, as shown and described.

DESCRIPTION

FIG. 1 is a perspective view of a first embodiment, of a dispensing bottle, according to the present invention.

FIG. 2 is an elevation view thereof.

FIG. 3 is a top plan view thereof.

FIG. 4 is a bottom plan view thereof.

FIG. 5 is an exploded view thereof.

FIG. 6 is another exploded elevation view thereof.

FIG. 7 is an elevation view of the outer cap thereof, shown without the bottle for ease of illustration.

FIG. 8 is a top plan view of the outer cap thereof, shown without the bottle for ease of illustration.

FIG. 9 is a bottom plan view of the outer cap thereof, shown without the bottle for ease of illustration.

FIG. 10 is an elevation view of the inner cap thereof, shown without the bottle for ease of illustration.

FIG. 11 is a top plan view of the inner cap thereof, shown without the bottle for ease of illustration.

FIG. 12 is a bottom plan view of the inner cap thereof, shown without the bottle for ease of illustration.

FIG. 13 is a perspective view of a second embodiment, of a dispensing bottle, according to the present invention.

FIG. 14 is an elevation view thereof.

FIG. 15 is a top plan view thereof.

FIG. 16 is a bottom plan view thereof.

FIG. 17 is an exploded elevation view thereof.

FIG. 18 is another exploded elevation view thereof.

FIG. 19 is an elevation view of the outer cap thereof, shown without the bottle for ease of illustration.

FIG. 20 is a top plan view of the outer cap thereof, shown without the bottle for ease of illustration.

FIG. 21 is a bottom plan view of the outer cap thereof, shown without the bottle for ease of illustration.

FIG. 22 is an elevation view of the inner cap thereof, shown without the bottle for ease of illustration.

FIG. 23 is a top plan view of the inner cap thereof, shown without the bottle for ease of illustration; and,

FIG. 24 is a bottom plan view of the inner cap thereof, shown without the bottle for ease of illustration.

The broken lines in the figures illustrate the portions of the designs that form no part of the claimed design.

The broken lines of FIGS. 6 and 18 are included to show the relationship of the bottle, outer cap, and inner cap only, and form no part of the claimed design.
